GLOW PLUG

Hermann I. A. Dorner and Adolph Widmann,
Detroit, Mich., assignors, by mesne assignments,
to Packard Motor Car Company,
Detroit, Mich., a corporation of Michigan

Application January 31, 1930. Serial No. 424,987

7 Claims. (Cl. 123—145)

This invention relates to internal combustion engines and more particularly to devices, known as glow plugs, for assisting the combustion of fuel charges in Diesel type engines.

Glow plugs are provided with a resistance wire which is usually coiled in a more or less free relation and with the ends fixed one to the electrode and the other to the plug body, the coil portion projecting into the main combustion chamber with many types of engines. Diesel engines require a compression of approximately five hundred pounds per square inch in the cylinder in order to ignite the charge and, furthermore, the compressed air within the cylinder is usually revolved at a high speed so that fuel sprayed therein will be well distributed. It is the most efficient practice to place the loosely wound portion of the glow plug resistance wire into position where the fuel can be sprayed thereagainst when it is introduced into the combustion chamber, such fuel in high speed engines being under a pressure of more than two thousand pounds per square inch. It will thus be seen that due to the above conditions, the glow plug is subjected to high compression and explosion pressures, to an intense heat, to the pressure of the fuel and the turbulence, and also inasmuch as the fuel is sprayed directly against the resistance wire, it is subjected to the highest temperature within the combustion chamber. These conditions maintain the resistance wire at a high temperature, even when not connected with a source of electrical supply, and while in such highly heated condition the effect of pressure tends to distort the free portion of the resistance wire and to loosen or break the wire at its points of attachment, such loosening being also caused by the difference in the degree of expansion of the other glow plug elements. As a result, the life of glow plugs with high speed Diesel types of engines is very short, and an object of the invention is to provide a glow plug in which the life is materially increased over those now known.

Another object of our invention is to provide a glow plug in which an end of a resistance wire is attached to an electrode in a manner such that it will not readily become loose or broken.

A further object of our invention is to provide a glow plug in which an intermediate portion of the resistance wire is related with the electrode so that vibration between such portion and the end fastened to the electrode is substantially eliminated.

A still further object of our invention is to provide a glow plug structure in which the length

of the air gap, adjacent the end of the electrode projecting into the engine cylinder, is very small.

These and other objects of the invention will appear from the following description taken in connection with the drawing, which forms a part of this specification, and in which:

Fig. 1 is a medial sectional view through a glow plug incorporating my invention;

Fig. 2 is an elevational view of the same;

Fig. 3 is a sectional view taken on line 3—3 of Fig. 1.

Referring now to the drawing by characters of reference, 10 represents a core which will be termed the electrode. The terminal member 11 surrounds one end of the electrode and a flange 12 is formed on the end of the electrode to secure the terminal in position. The opposite end 13 of the electrode is enlarged and includes a flange 14 at its inner end and an annular recess 15 adjacent the other end. A sleeve 16, formed of insulation material, surrounds the electrode intermediate the terminal 11 and the flange 14. Insulating disks 17 are telescopically arranged around the sleeve 16 adjacent the flange 14 and are clamped against the flange by one of a pair 75 80 of complementary collars 18 and 19.

A body 20 serves as a carrier for the other elements of the glow plug and the electrode extends through such body, a nut 21 being screwed into the body in a manner such that it will wedge 85 the member 18 against the member 19 and secure the insulation 17 in position. The member 18 is seated at its end against a gasket 22 which bears against a shoulder 23 formed interiorly of the body. A plurality of insulating disks 24 encircle the sleeve 16, intermediate the member 18 and the terminal 11, and a portion of such disks are surrounded by the hollow nut 21. The end of the body through which the enlarged portion of the electrode extends is of a diameter such that there will be an air gap around the electrode and extending only a very short distance longitudinally of the glow plug. The body is provided with a head 25 to which a tool can be applied to screw the plug into and out of an opening in an 90 95 engine cylinder wall.

One end of a resistance wire extends into a recess 26 in the end wall of the body and is fixed therein by a wedge element 27 pressed transversely of the end of the resistance wire. The other end of the resistance wire projects through a hole 28 in the electrode, such hole being off center and extending transversely of the axis of the electrode and exteriorly of the body 20. The end 29 of the resistance wire extending through the 100 105 110

electrode hole extends preferably in the same plane with the hole and is bent to conform with the shape of the electrode, the extreme end being welded to the electrode as indicated at 30. 5 The bent end portion of the resistance wire is originally formed so that it is slightly spaced from the electrode, thus allowing the portion adjacent the weld to shrink to the form of the electrode and thereby eliminate breakage which 10 would be caused if the shrinkage were not allowed for. A portion 31 of the resistance wire is wound spirally from the hole 28 toward the end of the electrode and is coiled twice within the recess 15 from which it extends a short distance beyond 15 the end of the electrode in the form of a loosely wound coil, and then extends in a reverse direction in a coil of increasing diameter telescoping the portion 31 which is closely associated with the electrode. A short length of the wire portion 31, 20 where it projects from the electrode, is bent outwardly as indicated at 32 so that it is spaced from the electrode in a manner providing resiliency and an angle such that the wire is not subjected to the bending stresses due to vibration 25 which would be present if it closely followed the peripheral wall of the electrode at this point. The coiling of the wire closely around the electrode and its passage through the hole provide only a support while the weld provides the sole 30 contact between the wire and the electrode through which the current passes.

It will be seen that we have provided a simple manner of attaching the end of the resistance wire to the electrode so that it will remain secure during a long period of engine operating 35 time without becoming loose and without breaking. Such results are also assisted by the manner in which the portion 31 of the wire is wound around the electrode and seated tightly within the 40 recess 15. Such arrangement permits the loose portion of the coil a certain degree of movement and expansion without imparting bending stresses to the portion adjacent that secured to the electrode and without disturbing the contact 45 weld.

While we have herein described in some detail a specific embodiment of our invention, which we deem to be new and advantageous and may 50 specifically claim, we do not desire it to be understood that our invention is limited to the exact details of the construction, as it will be apparent that changes may be made therein without departing from the spirit or scope of our invention.

55 What we claim is:

1. In a glow plug for internal combustion engines having a body and an electrode insulated and projecting from the body, said projecting portion of the electrode having a transversely extending hole therethrough, heating means comprising a resistance wire fixed at one end to the body, the other end of the wire extending through the hole and the projecting portion being par-

tially coiled against the electrode for support and welded thereto for a contact.

2. In a glow plug for internal combustion engines having a body and an insulated electrode projecting from the body, heating means comprising a resistance wire fixed at one end to the body, a portion of the wire being coiled closely around and projecting through the electrode with the end fixed to the electrode, a portion of the wire coiled around the electrode adjacent the portion extending through the electrode and the closely coiled portion being bent to extend in spaced relation from the electrode.

3. In a glow plug for internal combustion engines having a body and an insulated electrode 90 extending through the body, one end of the electrode having a portion of reduced diameter forming a recess, heating means comprising a resistance wire having one end fixed to the body and the other end fixed to the electrode, a portion of 95 the wire adjacent the end fixed to the electrode being coiled closely against the electrode in the recess.

4. In a glow plug for internal combustion engines having a body and an electrode insulated 100 from and extending through the body, one end of the electrode having a circular recess there-around, heating means comprising a resistance wire fixed at one end to the body and at the other end to the electrode adjacent the body, said wire 105 adjacent the end fixed to the electrode being coiled closely against the electrode and in the recess and then continued as a coil in spaced relation from the electrode toward the end fixed to the body.

110 5. In a glow plug for internal combustion engines of the Diesel type having a body and an electrode projecting from the body, heating means comprising a resistance wire fixed at one end to the body and welded at the other end to 115 the electrode to form the contact, said wire being supported in a shock absorbing relation upon the electrode adjacent the welded portion thereof.

6. In a glow plug for internal combustion engines of the Diesel type having a body and an 120 electrode projecting from the body, heating means comprising a resistance wire fixed at one end to the body and welded at the other end to the electrode to form a contact, the end of the wire adjacent the welded portion being coiled 125 close against the electrode and passing transversely therethrough intermediate the ends of the coil.

7. In a glow plug for internal combustion engines of the Diesel type having a body and an 130 electrode projecting from the body, heating means comprising a resistance wire formed in two telescoping coils, the free end of the outer coil being fixed to the body and the inner coil closely 135 engaging the electrode for support and being welded to the electrode for contact.
